UNITED STATES PATENT OFFICE.

JOHN L. SYMONDS, OF DETROIT, MICHIGAN.

DESIGN FOR A FLOWER-STAND.

SPECIFICATION forming part of Design No. 23,906, dated December 25, 1894.

Application filed October 8, 1894. Serial No. 525,300. Term of patent 7 years.

To all whom it may concern:

Be it known that I, JOHN L. SYMONDS, a citizen of the United States, residing at Detroit, in the county of Wayne and State of Michigan, have invented and produced a new and original Design for a Flower-Stand, of which the following is a specification, reference being had therein to the accompanying drawings, in which—

10 Figure 1 is a side elevation. Fig. 2 is a front elevation. Fig. 3 is a plan view of one of the shelves, and Fig. 4 is an enlarged elevation of one of the brackets.

15 A is a vertical rear bar standard, having the central twisted section B.

20 C is the front inclined standard, having twisted sections C', and terminating in a vertical foot, connected to the section C by a gracefully curved elbow. At the top and between the twisted sections of the standard C are the brackets D. These brackets have a horizontal bar a, terminating in an open scroll

at the outer end, and having the scroll ornamentation b on the under side extending to the inclined rear bar c. From the rear middle face of this bar c swells out the bar d, which extends in line with the bar c along the side of the standard C. On the brackets are the gridiron shelves E having the scalloped edging F.

30 G is a connecting bar between the lower ends of the standards having the rope shaped central bar G'.

What I claim as my invention is—

1. The design for a flower stand bracket, 35 substantially as herein shown and described.

2. The design for a flower stand, as herein described and shown.

In testimony whereof I affix my signature in presence of two witnesses.

JOHN L. SYMONDS.
